TAG BEARING SEAL

Mark Rubinoff, New York, N. Y., assignor to
Morris Canter, New York, N. Y.

Application November 25, 1938, Serial No. 242,154

9 Claims. (Cl. 40—2.2)

This invention relates to tag bearing seals for a tie cord, or a knot on the tie cord, looped to some article, to prevent the cord from being removed from the article or untied without mutilating the seal.

An object of this invention is to provide a seal on which there is mounted a tag which may carry information concerning the article to which the tie cord is attached.

10 A further object of this invention is to provide a seal of the character described, having means for normally covering the tag, said means being so constructed that the same may be uncovered to expose the tag to view, whereby the numbers, 15 marks or information printed thereon may be read.

A still further object of this invention is to provide a seal of the character described, having highly improved means for retaining the tag in 20 proper position and for effectively preventing the cord from being pulled out of the seal.

Still another object of this invention is to provide a strong and rugged seal of the character described, which shall positively lock when 25 moved to sealing position, which shall be relatively inexpensive to manufacture, easy to manipulate, and withal practical and efficient to a high degree in use.

Other objects of this invention will in part be 30 obvious and in part hereinafter pointed out.

The invention accordingly consists in the features of construction, combinations of elements, and arrangement of parts which will be exemplified in the construction hereinafter described, 35 and of which the scope of application will be indicated in the following claims.

In the accompanying drawing, in which is shown various possible illustrative embodiments of this invention,

40 Fig. 1 is a top plan view of the seal, before the seal is moved to sealing position;

Fig. 2 is a cross-sectional view taken on line 2—2 of Fig. 1;

Fig. 3 is a cross-sectional view taken on line 45 3—3 of Fig. 1;

Fig. 4 is a cross-sectional, elevational view of the seal collapsed to sealing position;

Fig. 5 is a cross-sectional view taken on line 5—5 of Fig. 4;

50 Fig. 6 is a cross-sectional view taken on line 6—6 of Fig. 4;

Fig. 7 is a top plan view of the seal shown in Fig. 4;

Fig. 8 is a view similar to Fig. 7, but illustrating a modified construction; and

Fig. 9 is a cross-sectional view taken on line 8—9 of Fig. 8.

Referring now in detail to the drawing, 10 designates a seal embodying the invention, having a tie cord 11 attached to a key or other article 12.

As shown in Fig. 4 of the drawing, the ends of the cord 11 are knotted, as at 14, and the knot is received within the seal, as will appear hereinafter. The knot portion of the loop cannot be 10 removed from the seal unless the seal is mutilated.

In Figs. 1 and 2, the seal 10 is shown in open position, before being collapsed to sealing position. As shown in Figs. 1 and 2, the seal 10 may be made of sheet metal and comprises a flat bottom wall 15, comprising wall portions 16 and 17, supported by a central intermediate bendable portion 18.

Extending upwardly from the sides of the portion 18 are upstanding parallel walls 19, and an upwardly curved end wall 20, interconnecting said parallel walls. The wall 16 is provided with a transverse strap 21, adjacent the curved end wall 20. The strap 21 is made from the material of the wall portion 16, by cutting two parallel slits and pressing the metal between the slits upwardly to form a strap or loop.

The wall portion 16 is formed with an upwardly punched indentation or projection 22, adjacent 30 strap 21. The strap 21 is located between the projection or indentation 22 and the curved wall 20.

The wall portion 17 is formed with an oblong window opening 23, for the purpose hereinafter 35 appearing.

Extending upwardly from the sides of said portion 17 are a pair of parallel walls 24. The walls 24 are closer together than the walls 19, so that when the wall 17 is folded over to the position shown in Fig. 4, the walls 24 will just fit within the walls 19. Each of the walls 24 is formed with a pair of inwardly extending punched prongs 25, disposed somewhat above the lower wall portion 17.

Extending upwardly from the end of wall portion 17, is a wall or tongue 26. The wall 26 is formed with an inwardly punched prong 28, pointing downwardly, for the purpose hereinafter appearing.

On wall 17, and covering the opening 23, is a tag 30, held against said wall by the prongs 25 on walls 24. The tag 30 may bear any suitable written or printed matter, for example, a mark or number describing or referring to the article 12 55

to which the seal is attached. The written matter or printed matter or marks may be read through the window opening 23.

The knot portion 14 of the cord or loop 11 is placed on the portion 18 of the seal, and the seal is then closed or bent about said portion 18, so that the wall portion 17 swings like a jaw toward the wall portion 16. As this operation is performed, the walls 24 move just inside of the walls 19, and the upper end of wall or tongue 26 moves within the curved wall 20 and is curved by said latter wall beneath the strap 21, to the position shown in Fig. 4 of the drawing. The prong 28 snaps beneath the strap 21, so as to engage said strap and prevent the seal from being opened without mutilation of the seal. The knot 14 is caught between the side walls of the seal, and the cord 11 presses outwardly between the bent portion 18 of the seal and the side walls 24.

20 It will now be understood that the seal cannot be opened except by mutilating the seal.

The upstanding tongue or wall 26 is preferably tapered upwardly, so as to be weakened toward the top to facilitate bending thereof as it is pressed against the inner surface of the curved wall 20.

In Fig. 8 there is shown a seal 10a, similar to the seal 10, with the exception that the wall portion 17 instead of having a window opening 23, is cut along parallel lines 40 and an interconnecting end line 41, to form a tab 42, for covering the tag 30. The tab 42 may be provided with a suitable extension 43 which is adapted to snap beneath the cut edge 41 to hold the tab in closed position. The tab may be pulled upwardly to expose the tag 30.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

50 1. A seal comprising a flat bottom wall having a central portion, and a pair of wall portions on opposite sides of said central portion, one of said pair of portions having a pair of parallel up-standing side walls, and an upwardly curved end wall, and being formed with a transverse upwardly extending strap, and an upwardly projecting indentation, adjacent said strap, whereby said strap is interposed between said indentation and curved wall, the other of said pair of wall portions 55 being formed with a pair of parallel upwardly extending side walls, and an upwardly extending end wall, said latter end wall being formed with an inwardly projecting prong, said seal being bendable about said central portion to bring the pair of parallel side walls on said other of said pair of wall portions within the pair of walls on the first of said pair of wall portions, the upwardly extending end wall being adapted to be bent beneath said strap, upon bending said seal, the other of said wall portions being formed with a window opening, the pair of side walls on said other of said wall portions being formed with inwardly extending prongs, and a tag covering said window opening and interposed between said last mentioned prongs and said other of said wall portions.

75 2. A seal comprising a flat bottom wall having a central portion, and a pair of wall portions on opposite sides of said central portion, one of said pair of portions having a pair of parallel up-standing side walls, and an upwardly curved end

wall, and being formed with a transverse upwardly extending strap, and an upwardly projecting indentation, adjacent said strap, whereby said strap is interposed between said indentation and curved wall, the other of said pair of wall portions being formed with a pair of parallel upwardly extending side walls, and an upwardly extending end wall, said latter end wall being formed with an inwardly projecting prong, said seal being bendable about said central portion to bring the pair of parallel side walls on said other of said pair of wall portions within the pair of walls on the first of said pair of wall portions, the upwardly extending end wall being adapted to be bent beneath said strap, upon bending said seal, the other of said wall portions being formed with a window opening, the pair of side walls on said other of said wall portions being formed with inwardly extending prongs, and a tag covering said window opening and interposed between said last mentioned prongs and said other of said wall portions.

3. A seal comprising a flat bottom wall having a central portion, and a pair of wall portions on opposite sides of said central portion, one of said pair of portions having a pair of parallel up-standing side walls, and an upwardly curved end wall, and being formed with a transverse upwardly extending strap, and an upwardly projecting indentation, adjacent said strap, whereby said strap is interposed between said indentation and curved wall, the other of said pair of wall portions being formed with a pair of parallel upwardly extending side walls, and an upwardly extending end wall, said latter end wall being formed with an inwardly projecting prong, said seal being bendable about said central portion to bring the pair of parallel side walls on said other of said pair of wall portions within the pair of walls on the first of said pair of wall portions, the upwardly extending end wall being adapted to be bent beneath said strap, upon bending said seal, the other of said wall portions being formed with a window opening, the pair of side walls on said other of said wall portions being formed with inwardly extending prongs, and a tag covering said window opening and interposed between said last mentioned prongs and said other of said wall portions.

4. A seal comprising a pair of jaws, and an intermediate bendable portion between said jaws, one of said jaws having a curved end wall, and a transverse strap adjacent said curved wall, and an upwardly projecting indentation adjacent said strap, whereby said strap is disposed between said indentation and curved wall, and the other of said jaws having at its outer end a tongue formed with a prong, said tongue being adapted to be guided by said curved wall beneath said strap, and the portion of the tongue which passes beneath said strap being adapted to be pressed upwardly by said indentation, whereby the prong on said tongue may engage said strap to retain said jaws against separation, after said jaws have been pressed together.

5. A seal comprising a pair of jaws, an intermediate bendable portion between said jaws, one of said jaws being formed with a window opening, a tag covering said window opening, means on said jaw to hold said tag in position overlying said window opening, interengaging locking means on said jaws adapted to interlock when said jaws are bent together about said inter-

mediate bendable portion, and means on said one of said jaws for covering said window opening.

6. A seal comprising a pair of jaws, and an intermediate bendable portion, one of said jaws having a curved wall, and a strap adjacent said curved wall, and the other of said jaws having a tongue formed with a prong adapted to be guided by said curved wall beneath said strap, whereby said prong may engage said strap to retain said 10 jaws against separation, after said jaws have been pressed together, one of said jaws having a window opening, a tag covering said opening, means on said jaw to hold said tag in window covering position, and means on said jaw to cover said 15 window opening and tag.

7. A seal comprising a pair of jaws, and an intermediate bendable portion between said jaws, one of said jaws having a curved end wall, and a transverse strap adjacent said curved wall, 20 an upwardly projecting indentation adjacent said strap, whereby said strap is disposed between said indentation and curved wall, and the other of said jaws having at its outer end a tongue formed with a prong, said tongue being adapted to be guided by said curved wall beneath said strap, and the portion of the tongue which passes beneath said strap being adapted to be pressed upwardly by said indentation, whereby the prong on said tongue may engage said strap to retain 25 said jaws against separation, after said jaws have been pressed together, one of said jaws having a window opening, a tag within said jaw covering said window opening, and means on said jaw to hold said tag in position overlying said 30 winding opening.

8. A seal made of metal and comprising a pair of jaws, and an intermediate bendable portion between said jaws, each of said jaws having a bottom wall and a pair of upstanding, longitudinal, parallel walls, the parallel walls of one of the jaws being adapted to be received within the parallel walls of the other of said jaws, when the seal is bent about its intermediate portion to close said jaws, one of said jaws having an upwardly curved end wall and being formed with a pair of transverse parallel slits adjacent said 40

curved wall, the metal between said slits being pressed upwardly to form a strap, and the other of said jaws having an upwardly extending tongue at its outer end adapted to be received within said curved wall, and guided thereby beneath said strap when the jaws are closed, and the jaw which has the curved wall being formed with an upwardly projecting indentation beyond said strap, whereby said strap is disposed between said indentation and curved wall, and said 10 indentation being adapted to press the portion of the tongue which passes beyond the strap, upwardly, and said tongue being formed with a prong adapted to engage the strap to prevent the jaws from being separated. 15

9. A seal made of metal and comprising a pair of jaws, and an intermediate bendable portion between said jaws, each of said jaws having a bottom wall and a pair of upstanding, longitudinal, parallel walls, the parallel walls of one of the jaws being adapted to be received within the parallel walls of the other of said jaws, when the seal is bent about its intermediate portion to close said jaws, one of said jaws having an upwardly curved end wall and being formed with a 20 pair of transverse parallel slits adjacent said curved wall, the metal between said slits being pressed upwardly to form a strap, and the other of said jaws having an upwardly extending tongue at its outer end adapted to be received within said curved wall, and guided thereby beneath said strap when the jaws are closed, and the jaw which has the curved wall being formed with an upwardly projecting indentation beyond said strap, whereby said strap is disposed between 25 said indentation and curved wall, and said indentation being adapted to press the portion of the tongue which passes beyond the strap, upwardly, and said tongue being formed with a prong adapted to engage the strap to prevent the jaws from being separated, one of said jaws being formed with a window opening, a tag within said jaw covering said window opening, and means on said jaw to hold the tag in position for covering 30 said window opening. 35

MARK RUBINOFF. 45
